(57) **CLAIM**

The ornamental design for a pharmaceutical kit, as shown and described.

DESCRIPTION

FIG. 1 is a perspective view of a pharmaceutical kit showing the inside portion thereof, in an unfolded position with an uninserted insert card;

FIG. 2 is front elevation view of a pharmaceutical kit showing the inside portion thereof, in an unfolded position without an insert card;

FIG. 3 is a bottom plan view thereof;

FIG. 4 is a back elevation view thereof;

FIG. 5 is a left elevation view thereof;

FIG. 6 is a right elevation view thereof;

FIG. 7 is a front elevation view of the insert card;

FIG. 8 is a back elevation view thereof;

FIG. 9 is a side elevation view thereof;

FIG. 10 is a bottom plan view thereof;

FIG. 11 is a perspective view of a pharmaceutical kit in folded position; and,

FIG. 12 is a perspective view of a pharmaceutical kit showing the inside portion thereof, in an unfolded position with a partially inserted insert card.

The broken lines shown in FIG. 4 represent fold lines, and the insert card shown separately in FIGS. 7-10 is for clarity of illustration only.
